UNITED STATES PATENT OFFICE.

JEAN A. LE ROY, OF NEW YORK, N. Y.

KINETOSCOPE.

1,027,135.

Specification of Letters Patent.

Patented May 21, 1912.

Application filed March 12, 1908. Serial No. 420,623.

To all whom it may concern:

Be it known that I, JEAN A. LE ROY, a citizen of the United States, and a resident of New York, in the county of New York and State of New York, have invented certain new and useful Improvements in Kinetoscopes, of which the following is a specification.

My invention relates to kinetoscopes or moving picture outfits; and it has for its object an outfit of this character which shall be simple in its construction and shall be properly safeguarded against the firing of the film. I obtain this object in the outfit 15 shown in the accompanying drawings, and in which—

Figure 1 is a partial rear elevation of the film moving mechanism and attachments. Figs. 2 and 3 are partial side elevations of 20 same. Fig. 4 is a detail view of the face plate and intermittent sprocket, and part of movement therefor. Fig. 5 is a detail view of the shaft bearing for the intermittent sprocket. Figs. 6 and 7 are views illustrating the centrifugally operating means for the automatic, film protecting fire shutter. Fig. 8 is a view illustrating the drive for the film take-up reel. Fig. 9 is a top view of a truss holder for the table legs. 25 Fig. 10 is a view illustrating the truss holder bent into proper position and secured to the table. Fig. 11 is a front elevation, and Fig. 12 is a side elevation of a lamp house shutter. Fig. 13 is a side elevation 30 of the lamp house and film operating mechanism mounted on an operating table.

Similar characters of reference designate corresponding parts throughout the several views.

Referring to the drawings, Fig. 13, it 40 designates the lamp house containing a suitable source of light, such as an arc light (not shown), and is adjustably mounted in the usual manner, upon a table T. The light is projected through the condensing lens L to the film operating device D, likewise mounted upon the table T, and drawing the film F from the upper film reel R and winding the same upon the lower film 45 reel S when the handle 10 is turned.

The table T rests upon the usual, telescopic legs 11—two at each end—but is further braced by the struts 12 which are removably attached to these legs and also re-

movably fitted to the truss holder 13, being held by the four arms 16. The truss holder 13 is removably attached to the table T by means of the headed bolt and thumb nut 14, the projections 17 as well as the ends of the arms 16 abutting the underside of the table T.

A shutter frame 18 is fastened to the inner wall 19 of the lamp house H and between the source of light and the condensing lens L and is so designed as to permit the passage of the light under normal conditions through the aperture 20. This frame is arranged as shown in Fig. 12 to provide a ventilating air space 21, and the top and bottom thereof is provided with slots 22 to permit of the circulation of the air. Within the frame 18 is slidably mounted a shutter 23 operated by the slotted arm 24 which fits over a pin 25 of said shutter. When in the dotted position, shown in Fig. 11, the shutter 23 prevents the passage of the light through the aperture 20 to the condensing lens L. By the use of this shutter the life of the condensing lens L may be considerably prolonged, as the light can be readily cut off when not in actual use; and the space 21 and slots 22 induce a circulation in the lamp house itself.

The film F after leaving the reel R passes through the device D being drawn therethrough by the action of usual feed sprocket 30, intermittent sprocket 31 and take-up sprocket 32, passing then to the lower take-up reel S. These sprockets are operated in the usual manner by the well-known mechanism, in turning the handle 10.

The shaft 33 of the intermittent sprocket 31 is mounted in a special double eccentric bearing 34, 35, for the purpose of adjusting the sprocket 31 with respect to the runners 36 of the face plate 37 to enable the film to be properly taken from said runners. The said shaft 33 is mounted eccentrically in the bearing 34 which is eccentrically mounted in the bearing 35 and held thereto by means of a set screw 35' in a position approximately correct for taking the film from the runners 36, the final adjustment being made, however, by turning the bearing 35, mounted in bearing 38 of frame 39 by means of a handle 40. The said bearing 35 is then fixed by suitably securing the same to the frame 39 as by means of a set screw 40'.

The outer end of the shaft 33 carries the usual star wheel 41 of the Geneva movement, imparting the intermittent motion to the sprocket 31. A hub 42 attached to this star wheel is provided with annular groove (not shown) on its inner face; and a corresponding groove 43 is provided in the bearing 34 (Fig. 5) about the shaft 33, said grooves being adapted to retain a number 10 of balls 44 providing thereby a ball-bearing for the star-wheel against the frame 39, or rather bearing 34. This practically eliminates friction between the star wheel and the frame. The handle 40 is omitted in Fig. 4 to 15 permit of the view of the balls 44.

In Fig. 2 I have shown the grooves 45 of the star-wheel 41 cut entirely through, the shaft 33 being flush with the bottom of said grooves, whereby the striking of the pin 46 20 is avoided and the said pin may be made of larger diameter, diminishing thereby the wear of same.

The entire film moving mechanism is mounted on the frame 39 and is vertically 25 adjustable upon standards 51 and 52. The face plate 37, as well as the gate 53 and other apparatus hereinafter set forth, is rigidly held to the standards 51 and 52 through the arm-piece 54. A relative motion between 30 these two parts of the machine is obtained by means of the rack 55, rigid with respect to the standards, being secured to the front plate 58; and a segmental gear 56 meshing therewith and pivoted to the frame 39, the 35 said gear being operated by means of a removable lever 57. As the gear 56 is turned, the frame 39, with the entire film moving mechanism is correspondingly raised or lowered, thereby affording means for properly framing the pictures of the film with 40 respect to the aperture 59 in the face plate 37.

To the gate 53 is secured a shield or curtain 60 covering the rear of the machine below said gate, and provided with side or wing pieces 61. This shield with its wing pieces is designed to reduce the fire hazard by preventing the film, in case of breakage, from running out of the machine as a result 50 of collecting and bunching after leaving the take-up sprocket 32. The upper part of the gate is likewise provided with a cup-shaped, loop protecting shield 62 which is designed to protect the film loop against falling down 55 over machine, due to the slipping or jumping of the film on the feed sprocket, whereby the same would be exposed to the danger of ignition by the projected light. This protecting curtain and shield being secured 60 to gate 53, will swing with the same when it is opened, after first raising the latch 63, Fig. 1, pivoted to the said gate and fitting over the pin 64 which passes through said gate and is secured to the face plate 37.

65 To the gate is hinged a safety fire shutter

70, provided with a laterally extending arm 71. This arm 71 is arranged to be engaged by a depending arm 72 when the film moving mechanism is in motion, the said arms 72 moving outwardly and thereby raising 70 the safety shutter 70 so as to permit the light projected from the lamp house II to pass through the aperture 59 to the film. So soon, however, as the film moving mechanism slows down, or stops, the arm 72 drops back into normal position and likewise the safety fire shutter 70, thereby shutting off the intense projected light which, passing through the aperture 59, would in a few seconds cause the ignition of the film moving 75 at a slow rate of speed, or at rest.

The arm 72 is controlled by a centrifugal mechanism shown in detail in Figs. 6 and 7. This mechanism consists essentially of an outer shell 73 to which the arm 72 is 80 fixed, and within which is arranged to rotate a disk 74. Pivotedly mounted on this disk and near the circumference thereof, are a number of centrifugal arms 75. The said disk is provided with a shaft 76 which fits in a bearing 77 of the shell 73, the shell and disk being held together by means of washer 78 and screw 79 screwed into the said shaft 76. The said shaft 76 is mounted within a bearing 80 of the fixture 81 which is secured 85 to the frame 39. The shaft 76 is driven from the driving wheel 82 through intermediate gearing comprising the gear wheels 83, 84 and 85, the last being on the shaft 76. As the driving wheel 82 is turned, rotation 90 is communicated to the disk 74 causing the centrifugal arms 75 to fly outwardly and make frictional contact with the inner surface of the shell 73, whereby the same tends to rotate and lifts the safety fire shutter as 95 explained.

The two parts of this device—the fire shutter, and the centrifugal mechanism are 100 separate and are independently attached, the former being an integral part of the gate, and the latter of the moving mechanism, whereby the relative vertical movement of the film mechanism in framing the pictures of the film will not disturb the action of this shutter device. The two parts may also be 105 readily affixed to a machine already completed, requiring no alteration or change of parts being simply added thereto by inter-gearing with the film moving mechanism.

After the film leaves the film moving 110 mechanism D, it is wound up on the take-up reel S, which is driven through a pulley 90, to which a pulley 91 of the film moving mechanism transmits motion through a belt 92, Fig. 8. This belt passes over two idlers 115 93 placed side by side and supported by an arm 94 attached to the standard 52.

The addition of the idlers provides against 120 excessive and serious variation in the tension of the belt 92, which would otherwise 125

result from the raising and lowering of the frame 39 in framing the pictures of the film.

I claim:—

1. In a kinetoscope: a frame, a film, and film moving mechanism movable as a whole relatively to said frame; a face plate, and a gate hinged thereto having registering apertures, said face plate being fixed to said frame; and means to vertically adjust the entire film moving mechanism to properly frame the picture of said film with respect to the aperture of said face plate and gate.

2. In a kinetoscope: a frame, a film, and film moving mechanism movable as a whole relatively to said frame; a face plate, and a gate hinged thereto having registering apertures, the said face plate being fixed to said frame; a rack fixed to said frame; and a segmental gear pivoted to said film moving mechanism adapted to engage with said rack to vertically adjust said entire film

moving mechanism to properly frame the picture of said film with respect to the apertures of said face plate and gate.

25

3. In a kinetoscope: a film and film moving mechanism; a frame; a take-up reel for said film; a driving pulley operated by said film moving mechanism and adjustable relatively to said reel; a driven pulley for said reel; a belt or the like connecting said former pulley with said reel pulley to transmit motion thereto; an arm attached to said kinetoscope frame; and two idlers carried by said arm upon its outer end and upon which are carried respectively the two branches of said belt or the like.

Signed at New York, in the county of New York and State of New York, this 7th day of March A. D. 1908.

JEAN A. LE ROY.
